UNITED STATES PATENT OFFICE.

HOWARD PARKER, OF BERLIN, NEW HAMPSHIRE, ASSIGNEE TO BROWN COMPANY,
OF BERLIN, NEW HAMPSHIRE, A CORPORATION OF MAINE.

REINFORCING ENDS OF CAPS FOR FIBER TUBES.

Application filed January 19, 1926. Serial No. 3,258.

This invention relates to tubular cores or mandrels on which a roll of paper is wound and more particularly to the metal caps or reinforcing ends thereof.

5 The cores of the desired diameter are usually produced from fibrous material such as cloth, paper or pulp. In some cases, where paper or cloth is employed for the purpose, the convolutions thereof are united 10 or cemented together by any suitable material, and in others the core is made by winding a web of wet cellulose pulp upon a mandrel in such manner as to produce a nonlaminated wall of inter-felted cellulose 15 fibers.

A tubular core, such as herein referred to, according to the present invention is provided at each end with a notched cap of novel construction as will be hereinafter 20 pointed out.

On the accompanying drawings,—

Figure 1 represents the metal cap ready for placement upon the end of a fiber core or mandrel.

25 Figure 2 represents a longitudinal section of the end of a core having the cap thereon.

Figure 3 represents one form of reinforcing member which is employed as a portion of the cap.

30 Figure 4 represents one end of the core.

Figure 5 represents another form of the end cap.

Figure 6 represents a section on the line 6—6 of Figure 5.

35 Figure 7 represents a slightly different form of cap.

Figure 8 represents a sectional reinforcing member such as may be used therein.

Figure 9 represents a section on the line 40 9—9 of Figure 7.

Figure 10 shows another form of an annular sectional reinforcing member.

Figure 11 illustrates a part of the cap with said member indicated in dotted lines.

45 Figure 12 illustrates a cap with a different form of reinforcing member.

Figure 13 shows a section therethrough, with a part of the inner sleeve broken away.

Figure 14 shows the reinforcing member.

50 Figure 15 shows the recessed end of the core.

Figure 16 illustrates the end of a core having a reinforcing member like that in Figure 14, but with the outer sleeve continuous.

Figure 17 represents a section on the line 17—17 of Figure 16.

Figures 18 and 19 illustrate another embodiment of the invention.

Figure 20 illustrates a core having a cap 60 with another form of reinforcing member.

Figure 21 represents a section on the line 21—21 of Figure 20.

Figure 22 represents the reinforcing member.

On the drawings, the core or mandrel is indicated at 10 and it consists as ordinarily of a tube of the proper length and diameter, only one end portion of the tube being shown. It will be understood that each end 70 of the core or mandrel is provided with one of the caps or metal reinforcing ends which I shall now describe.

Each cap is formed of a single sheet of 75 sheet metal which is subjected to a series of drawing operations by means of suitable presses so that it finally consists of an inner sleeve 11, an outer sleeve 12, and a rim 13 which integrally connects the inner and outer sleeves. These sleeves and the integral rim are relatively light in weight and possess great strength. Between the sleeves there is an annular recess of proper dimensions to receive the end of the core, which preferably is rabbeted internally and externally to a depth equal to the thickness of the sleeves.

In this annular recess as shown in several of the figures, there is inserted a metal reinforce 14 so as to bear against the inner surface of the rim and against the confronting surfaces of the sleeves 11 and 12. The reinforce may be formed in various ways such as hereinafter described, but in any event it is so constructed as to afford a 80 notch therein. For example the reinforce 85 may be formed as a ring as illustrated in Figure 3 with a gap or notch therein such as indicated at 15. In this case the lower end of the notch may be bridged as indicated at 16. It is not necessary, of course, that the reinforce should be formed in one piece.

It may, for example, consist of two or more sections, as in Figure 8, wherein the reinforce is indicated as comprising the two split ring sections 17, 18, whose separated ends afford a notch 19 and another split ring section 20, the spaced ends of which are opposite the notch 19. In this case the section 100 20 affords a bridge 21 closing the lower end of the notch 19. In the event that the ring 105

110

Figure 13 shows a section therethrough, with a part of the inner sleeve broken away.

Figure 14 shows the reinforcing member.

Figure 15 shows the recessed end of the core.

Figure 16 illustrates the end of a core having a reinforcing member like that in Figure 14, but with the outer sleeve continuous.

is formed of two or more sections, they may be, if desired, spot-welded at one or more points so as to rigidly connect them together. Or the reenforce may consist of a relatively 5 wide ring section 22 having a gap or notch 23 between its ends, and a single narrow section 24 which bridges the gap 23, as shown in Figures 10 and 11. For light cores of the cheaper grade, a split ring 221 of less 10 width than the depth of the notch 222 in the inner and outer sleeves, may be employed as the reenforce as shown in Figures 18 and 19, in which case it is preferably spot-welded at several points to the sleeves, as indicated 15 at 223, 224. The ends of the annular member are flush with the walls of the notches in the sleeves.

It is not wholly essential that the metallic reenforce should be annular and occupy the 20 entire end or bottom of the annular recess of the cap, since it may consist of a single arcuate block or short section 25 having a gap or notch 26, as shown in Figures 13 and 14. In this case, it is especially desirable 25 to electrically spot-weld the reenforce to the sleeves at points on both sides of and below the notch as indicated at *a*, *b* and *c*. In this instance the end of the core may be slotted or recessed to receive the reenforce, 30 as shown at 10^a, Figure 15.

When a reenforcing member is employed, as last described, only the rim and the inner sleeve need be notched, as shown in Figures 16 and 17, in which case the outer 35 sleeve is continuous or unnotched, having a wall 261 closing the outside of the notch in the cap. The reenforcing member need not be solid. It may be made of a thin strip of angle iron bent or drawn substantially into 40 U shape as shown in Figure 22 at 262 and having the lateral flanges 263, 263 which lie in parallel planes. The web 264 which connects the flanges 263, constitutes a wall which defines the notch in the cap, and it 45 lies between the two sleeves of the cap and lies flush with the edges formed by cutting a notch or recess in the sleeves and rim of the cap. The flanges 263 are electrically welded to the inner confronting faces of 50 the sleeves.

One or both sleeves 11 and 12 and the rim 13 in all the embodiments of the invention are notched or cut away, but in some cases this is done in such manner that a portion 55 of the metal of the inner sleeve or the outer sleeve as the case may be is forced across the side walls of the notch in the ring. In Figures 1 and 2, for example, the metal (which ordinarily forms a part of the inner sleeve) is drawn radially outwardly so as to project through the notch in the ring and thus cover the walls of the notch as indicated at 27. As a result of this construction, 60 the cap is provided with a notch or recess 65 extending entirely therethrough so as to re-

ceive the projection or clutch on the driving member by which the finished core is rotated in winding a web thereon. While the metallic cover for the walls of the notch in the reinforce may be afforded by drawing or 70 forcing the metal of the inner sleeve through the notch in the surface, it may, however, be accomplished by forcing the metal of the outer sleeve inwardly through the notch as shown at 28 in Figure 5. Where a reenforce 75 such as shown in Figure 8 is used, the metal of the inner sleeve may be drawn outwardly so as to cover the side walls as at 280 in Figure 7 but not the bottom wall of the notch in the ring, leaving the upper face of 80 the lower section 21 of the ring exposed.

In the constructions, shown in Figures 1 to 11, the end of the fiber core abuts solidly against the annular reenforce, the latter itself being of a width at least as deep as the 85 notch in the whole metal end; and consequently it is wholly unnecessary to notch the end of the fiber core to coincide with the driving notch in the cap. The lip or flange, which extends across the walls of the notch 90 in the annular reenforce, in the last mentioned figures, securely locks the ring against rotative movement within the sleeves, and may receive the thrust of the driving member by which the finished core is rotated. 95 If desired, however, the annular reenforce may at one or more points be spot-welded to the inner or outer sleeves or both.

Where a drawn metal cap member is placed upon a fiber core so that the end of the core abuts against the rim 13, or where it is spaced from the rim 13, in either case the drawn metal walls of the notch and the ends of the finished core are frequently so 100 distorted and bent by the rough handling to which the cores are subjected in the ordinary mill, that the core is rendered useless and will not properly fit the driving members by which it is rotated. By employing as a part of the one-piece member, that is, 105 the drawn metal portion of the cap, a rigid reenforcing member which fills the end of the annular recess between the inner and outer sleeves on both sides of the notch, the cores may be handled roughly and thrown 110 about without materially damaging or misshaping or distorting the ends thereof. By 115 this construction also there is afforded a relatively light and cheap cap of greater strength and endurance or durability than has heretofore been afforded. The core may be held against axial movement relatively to the end caps by spinning or forcing the extremities of the sleeves into the inner and outer faces of the tube or by forming indentations in the outer sleeve which project into similar indentations in the fiber core.

Preferably, however, in order to prevent any 120 possibility of a relative movement of the core and the cap, where there is employed a 125 130

- reenforcing member against which the end of the core abuts, either or both of the two sleeves may be formed with projections 29 extending into the annular space between the sleeves. These are formed by forcing or drawing the metal of the sleeves so that the internal projections provide keys to occupy a slot 30 formed in the end of the core as shown in Figures 1, 2, 4 and 18. The cavo-convex keys 29 may touch each other, and in any event they are usually formed out of alinement with the notch in the cap. 5
- What I claim is:—
1. A core cap comprising an inner sleeve, an outer sleeve and an integral connecting rim all formed of sheet metal, and providing an annular recess between said sleeves, and a metal reenforce seated in said recess, said reenforce and the inner and outer sleeves and said rim having a notch open internally and externally of said cap to receive a driving member. 15
  2. A core cap comprising a one-piece drawn sheet-metal member having an inner sleeve, a concentric spaced outer sleeve and an integral rim, and a notched reenforce seated against said rim between the inner and outer sleeves, said metal member having a flange or lip extending into the notch in said reenforce and seated against the wall thereof. 25
  3. A core cap comprising a one-piece drawn sheet-metal member having an inner sleeve, a concentric spaced outer sleeve and an integral rim, and a notched reenforce seated against said rim between the inner and outer sleeves, and one of said sleeves having a portion extending radially of the cap into the notch in said reenforce. 35
  4. A core cap comprising a one-piece drawn sheet-metal member having an inner sleeve, a concentric spaced outer sleeve and an integral rim, and a notched reenforce welded to both sleeves and seated against said rim between the inner and outer sleeves, one of said sleeves having a portion extend- 40
  - ing radially of the cap into the notch in said reenforce and said sleeves and said rim having notches registering with the notch in the reenforce. 50
  5. A core cap comprising a sheet-metal member having spaced concentric inner and outer sleeves and an integral connecting rim, and an annular reenforce seated against the said rim between said sleeves, said sheet-metal member and said reenforce having a driving notch, and one of said sleeves having a radial portion projecting into the notch in the reenforce and covering the side walls thereof. 55
  6. The combination of a tubular core; and a cap therefor, said cap comprising a sheet-metal member having spaced concentric inner and outer sleeves and an integral connecting rim, and an annular reenforce located in the annular space between the inner and outer sleeves and seated against said rim; the tubular core having its end projecting into said annular space and seated against said reenforce; and said cap having a notch or recess to receive a driving member. 60
  7. A core cap, comprising an outer sleeve, an inner sleeve and an integral connecting rim forming an annular recess, and provided with a driving notch,—one or both of said sleeves having a portion thereof, spaced from the rim and from the notch, projecting into the annular recess to provide a key to enter a slot in the core. 65
  8. A core cap, comprising an outer sleeve, an inner sleeve and an integral connecting rim forming an annular recess, and provided with a driving notch,—said sleeves having confronting projections spaced from said notch and extending into the annular recess to provide a key for engaging a slot in the core. 70
- In testimony whereof I have affixed my signature.

HOWARD PARKER.
